RIFLE

Nicholas L. Brewer, Agawam, Mass., assignor to
 Savage Arms Corporation, New York, N. Y., a
 corporation of Delaware

Application November 8, 1937, Serial No. 173,358

7 Claims. (Cl. 42—16)

This invention relates to rifles and more especially to several features or constructions therein that will be used more particularly with single shot, handcocked rifles of the bolt action type.

The general purpose of my present invention is to provide a new and improved form of rifle and especially to provide several features that are most advantageously used in a single shot, handcocked rifle of the breech bolt action type as illustrated in the drawings herein although some features of construction are not limited in their use to the details of that type of rifle.

A further general purpose is to provide new features of construction or assembling and of operation which render the rifle simple and economical in construction and readily assembled and durable and effective in operation.

Further specific purposes or aims of this invention are as follows:

20 To form an enlargement of the extractor clearance cut on the barrel and form a circularly registering and axially adjacent cut in the wall of the head space recess at the front end of the breech bolt to provide a simple and effective vent for the escape of powder gases without injury to the shooter, and to provide a means of visually determining whether or not the chamber of the barrel is loaded with a cartridge without opening the action.

30 Further purposes and advantages of the invention will appear from the specification and claims herein.

The subject matter relating to the rebounding striker construction for firearms described herein and shown in the drawings hereof and formerly claimed herein has been made the basis for a separate and divisional application filed in the United States Patent Office July 23, 1938 as Serial No. 220,921. Similarly, the subject matter relating to the trigger and sear mechanism for firearms, described herein and shown in the drawings hereof and formerly claimed herein, has been made the basis for a separate and divisional application filed in the United States Patent Office on or about July 25, 1938 as Serial No. 221,094.

50 Fig. 1 is a right-hand side elevation of the material portion of a bolt action rifle illustrating my present invention, the adjacent part of the stock being in vertical section, the parts being in the position they occupy when the breech member is closed but the rifle not cocked.

55 Fig. 2 is a side view of the parts shown in Fig. 1 but omitting the stock, and with the breech member retracted.

Fig. 3 is a right-hand side elevation of the rear portion of the combination barrel and receiver; Fig. 4 is a rear view thereof. Fig. 5 is a side view of the striker-retaining bolt 17.

Fig. 6 is a side elevation similar to Fig. 2 but with the breech member closed and with the rifle cocked.

Figs. 7 and 8 are right side and top views respectively of the sear.

Fig. 9 is a side view of the trigger.

10 Fig. 10 is a right-hand side view of the breech bolt and parts mounted therein or thereon as seen at the angle where the handle projects directly up from the breech bolt, parts of the breech bolt adjacent the extractor and the handle being broken away to better show details of construction.

15 Fig. 11 is a right-hand elevation of the breech bolt and its assembled parts and the adjacent parts of the sear and trigger, in the position they occupy when the bolt is locked and when the striker is in rebounded or neutral position. Fig. 12 is a front-end view of the assembled parts of the breech bolt as seen in Fig. 11.

20 Fig. 13 is a vertical sectional view on an enlarged scale of the striker and its contained parts and of the rear half of the breech bolt and showing in side elevation a part of the firing pin near its rear end and the rear end of the sear, the parts being in the position they occupy when the striker is in rebounded or neutral position and when the said parts are seen from the left-hand side of the rifle. Fig. 14 is a view similar to Fig. 13 but with the parts in the position they occupy when the rifle is cocked. Fig. 15 is a view similar to Fig. 13 but with the parts in the position they occupy when the rifle has been fired but prior to the rebound of the striker.

25 Figs. 16, 17 and 18 are respectively top or plan, right side elevation and bottom views of the striker when the breech block is in locked position.

30 Figs. 19 and 20 are respectively side and edge views of the firing pin.

35 Figs. 21 and 22 are side and edge views of the extractor.

40 Fig. 23 is a vertical sectional view on an enlarged scale and looking forward on line 23—23 of Fig. 1.

45 Fig. 24 is a vertical sectional view on line 24—24 of Fig. 1 on a similar enlarged scale but looking rearwardly.

50 Fig. 25 is a diametrical sectional view as on line 25—25 of Fig. 23, through the forward end of the breech block and the adjacent portion of

55

the combined barrel and receiver and showing a cartridge in position, and looking in the direction indicated by the arrow in Fig. 23, that is outwardly along the bolt handle.

5 Fig. 26 is a cross sectional view on line 26—26 of Fig. 13 and showing the rear end of the firing pin and so its relative angular position in the chamber of the breech bolt directly in line with the striker 31.

10 Fig. 27 is a central vertical longitudinal sectional view of a modified form of mounting the upper end of the trigger in the receiver and Fig. 28 is a top or plan view of the relevant portion of the parts shown in Fig. 27.

15 Referring to the drawings in a more particular description it will be seen that the rifle illustrated is of the bolt action, single shot, hand loaded and hand cocked type and includes one member 25 being a combined or integrally formed barrel 26 and receiver 27 mounted above 20 the stock 28, a breech bolt 29 reciprocatingly mounted in the chamber 30 of the receiver with said breech bolt in turn having mounted therein a striker 31 normally controlled by the sear 32 25 and trigger 33.

The chamber 30 extends for the whole length of the receiver 27 to slidably receive therein the generally cylindrically shaped breech bolt 29. From this chamber there projects to the right 30 and for nearly one-third of the circle of the receiver the loading and ejecting aperture 34 and from the upper part of this aperture there is a narrower straight rearwardly extending passage 35 for the movement therethrough of the 35 inner end of the breech bolt handle 36. At the rear end of the lower half of the loading aperture 34 the receiver provides a forwardly facing shoulder 37 against which the rear face of the inner end of the bolt handle engages when 40 the breech bolt had been slid to forward position and then partly rotated to lock the same in forward position by downward movement of the said handle as is shown best in Figs. 1 and 6.

The relative form and shape of the loading 45 opening 34 and the passage 35 clearly appear from Fig. 3 which is a side view of the receiver 27 and the adjacent rearward portion of the barrel 26. As appears from Fig. 4 which is a rear view of the receiver and barrel, the rearward end 50 of the receiver at its lower part is provided with a guiding cut 38 wide enough and long enough to slidably receive therein the upper end of the upstanding finger 39 on the sear 32.

Transversely extending through the lower portion 55 of the receiver slightly forward from its rear end and slightly spaced from the guiding cut 38 there is provided an angularly disposed slot 40 which slopes forward as it extends downwardly and is adapted to loosely receive the correspondingly slanted upward projection 41 at the 60 upper and rear end of the trigger 33.

Immediately forward of the slanting projection 41 on the trigger, the trigger is provided with a forwardly extending straight portion 42 which 65 normally lies parallel to the adjacent lower surface of the receiver. Thereafter the trigger has a central straight portion 43, the upper portion of which extends through the aperture 44 in the sear 32. Conveniently but not necessarily the 70 opposite edges of this central portion of the trigger are provided with outwardly extending enlargements 45 which are immediately below the sear adjacent the aperture 44. As appears from Fig. 1, this central portion 43 of the trigger ex- 75 tends downwardly at right angles to the receiv-

er and through the main recess 46 in the stock provided to house the receiver and the sear and trigger and also through the secondary recess 47 extending entirely down through the stock for the passage there through of the trigger. Below this secondary recess 47 there is provided the ordinary trigger guard 48 into the opening of which the lower part 49 of the trigger extends for manual operation thereof in the usual way.

As is best shown in Figs. 7 and 8, the sear 32 10 is a combined sear and sear spring being formed of a relatively long bar of spring metal provided at its rearward end with the upstanding finger 39 already mentioned and provided a short distance forward thereof with the aperture 44 through 15 which the trigger passes. Adjacent the aperture 44 the sear is enlarged laterally and forward of this enlarged portion the sear extends forward still spaced from the lower side of the receiver and of the barrel almost to its forward end which 20 is offset upwardly and curved to fit the rounding face of the adjacent portion of the barrel. This combined sear and sear spring is secured to the barrel by the take-down lug 50, the lower part 51 of which is enlarged relative to its upper screw- 25 threaded portion 52 so that an upwardly facing shoulder 53 is provided bearing against the lower part of the front end of the sear. The arrangement and construction is such as to give a constant upward tension to the rear end of the sear 30 and thus hold the trigger in normal position as shown in full lines in Figs. 1, 2 and 3 but allowing a rearward pull upon the finger portion of the trigger to depress the sear to the position shown in dotted lines in Fig. 6, at which position the upper portion of the finger on the sear has become 35 disengaged from the striker 31. It will be obvious that the proper rearward pressure upon the lower or finger portion of the trigger will bodily swing the trigger. During such swinging operation, the 40 upper projection 41 on the trigger will act as a sliding fulcrum pivot for the trigger, and the lower surface of the forward part of the straight upper portion 42 of the trigger will bear against the upper face of the sear at the rear of the 45 aperture 44 and so swing the rear end of the sear downwardly. As soon as the sear is released from the striker the striker will shoot forward under the action of the combined main spring and rebound spring 75 and effect a firing impulse 50 upon the firing pin 82 as hereinafter described. As soon as the pressure of the shooter's finger is released from the trigger, the sear under its normal tension will return to normal position 55 carrying therewith the trigger to its normal position. The material of the receiver adjacent the rear side of the slot 40 will be upset or punched upwardly on both sides of the trigger finger 41 as at 56 and thus operate to hold the trigger 60 from any possibility of lateral displacement from the slot 40.

It will be noted that this mechanism of the sear and sear spring and the trigger is very easily constructed and easily and economically assembled and is strong and rigid and requires no additional or further parts other than the take-down lug 50 for holding the parts in place, and that no special parts or additional parts are required or used to form a pivot for the swinging of the trigger nor for the articulation of the trigger 70 against the sear.

In this rifle a special safety provision is incorporated by providing a simple and effective vent for the escape of powder gases without injury to the shooter in case a cartridge of the rim-fire 75

type such as used in this rifle explodes or bursts at the rim. It is one of the well known dangers of bolt-action rifles that such an explosion of a cartridge tends to allow the powder gases from explosion to travel back along the apparently tight fit of the bolt in the receiver and thus approach and sometimes reach the shooter's eye. My present safety feature consists in providing a positive and sufficiently large cut or clearance 57 on the right-hand side of the barrel immediately forward of the loading and ejecting aperture 34 and also by providing a cut or opening 58 at the forward end of the breech bolt 29. This forward cut or opening 58 in the breech bolt is at the right-hand side of the breech bolt when it is locked and is in extent about one-third of the circle of the said breech bolt and is, when the breech bolt is locked, directly opposite or to the rear of the clearance 57 cut in the barrel.

20 The detailed view Fig. 23 being taken on the vertical sectional line directly at the rear of the barrel shows the relative position and extent of the cut or clearance 57 in the barrel. The shade lines upon the cut 57 indicate the forwardly and outwardly tapering face of this cut on the barrel while the section lines indicate the extent of the receiver 27 that is left intact. The central circle represents the bore 59 of the barrel and the roughly semi-circular portion to the left of the center in this Fig. 23 represents the vertical rear face 60 of the barrel proper against which the forward side of the flange 61 of the rim-fire cartridge is forced and held by the forward movement and locked position of the breech bolt 29.

Fig. 25 which is a diametrical sectional view on line 25—25 of Fig. 23 indicates in the near part of the view the cut or clearance 57 which is upon the right hand side of the barrel. It will be noted particularly that this cut 57 tapers forwardly as it extends out to the extreme outer periphery of the barrel and allows a free vent directed forwardly for powder gases from a burst cartridge rim. It will be seen also from this view and also from other views in the drawings that this vent is entirely unobstructed and also that the cut or opening 58 in the breech bolt 29 is open directly out to the atmosphere and is not covered or obstructed in any way. While the opening 58 in the forward end of the breech bolt extends only through the breech bolt itself, it will be seen that the outer end of this opening is clear and unobstructed and particularly no part of the barrel nor of the receiver overhangs or covers the outlet therefrom. These two cuts 57 and 58 together form a very effective vent for the powder gases to escape directly to the right and away from the shooter's face in case a cartridge rim bursts and the gases pass laterally from the flange of the cartridge.

Fig. 24 being a vertical sectional view on line 24—24 of Fig. 1 or through the head space looking rearwardly and on an enlarged scale clearly indicates the circumferential extent of the cut 58 at the forward end of the breech bolt 29. This view is taken directly on the plane of the breech face or recessed forward face of the breech bolt. The breech face 63 is the flat face circular in shape and equalling in size the rear end of the cartridge; that is, the cartridge where it is enlarged by the presence of the cartridge flange 61. The head space is the distance between the plane of the breech face 63 and the plane of the rear face 60 of the barrel. The extent of this head space has to be very definitely fixed and

very positively positioned by the locking of the breech bolt in its forward position so as to hold the rear end of the cartridge accurately and very positively in place so that the cartridges will not be subjected to an abnormal or dangerous bursting force by the regular firing thereof. On the other hand, the extent of overhang of the flange of a cartridge beyond the circle of the cartridge chamber of the barrel is an element that varies considerably with different makes, styles and kinds of ammunition so that it is recognized that it is impracticable to support closely in a radial direction the periphery of the flange of the cartridge. However, if the cartridge is properly placed and held in the chamber of the barrel and its rear end properly and accurately supported by the breech face, the pressure from normal firing of the cartridge is not enough to rupture the periphery of the flange because the strength of the metal forming the rim of the cartridge is sufficient to hold, considering the slight inside area of the flange that is subjected to the pressure of firing. The forwardly projecting wall 64 about the breech face is not relied upon to touch or engage the periphery of the flange of the cartridge and the said wall is in no case effective to prevent the rearward passing of powder gases in case of the bursting of the rim of a cartridge. In this rifle, however, I have enlarged the cut through the wall 64 of the bolt head so as to provide not only for the extractor 65 but to provide a relatively wide extent of opening in the circle of the wall 64, for free and unobstructed escape of the powder gases from explosion laterally of the rifle and without giving any tendency for the gases to have to travel rearwardly of the breech bolt in order to escape. In Fig. 24 the breech bolt 63 is the inner circle bounded at its right hand part as seen in said view by the remaining portion of the wall 64 of the breech bolt and bounded on the left as seen in this view by the dotted line. Beyond out to the outer periphery of the breech bolt there is shown the cut 58 which it is seen extends for substantially one-third of the periphery of the bolt head.

The cut or clearance 57 in the right hand side of the rear end of the barrel also provides more than the necessary amount of clearance for the hook 66 on the forward end of the extractor to advance into as the breech bolt is moved straight forward as the inner end of the handle 36 travels through the passage 35 and as the said hook springs over and settles down into holding position over the forward edge of the flange 61 of the cartridge. This cut or clearance 57 also provides room for the said hook to travel downwardly around the necessary part of the circle formed by the forward face of this cut 57 as the breech bolt is rotated into locked position by the swinging down of the handle 36 immediately forward of the shoulder 37 and until the inner portion of the handle engages the edge 67 of the receiver at the lower side of the loading aperture 34. As the longitudinally extending arm of the extractor 65 is narrower than the width of the inner part or base of the handle 36 and in fact preferably has its center line substantially in the center line of the said base of the handle as appears from Fig. 24, there is a space between the hook 66 of the extractor and the therebelow edge 67 of the receiver which space affords a vent even below the extractor for the escape of powder gases if required. The presence of this space below the extractor is plainly seen in Fig. 1. In that figure also as well as in Fig. 6 there is shown

the very much larger space above the hook of the extractor where the cut or clearance 57 in the barrel and the cut or opening 58 in the breech bolt are entirely clear of any obstruction 5 even from the extractor. The forming of the cut or clearance 57 in the barrel for a greater part of the circle of the barrel than is required for the partial rotation of the extractor as the breech bolt is partially rotated eliminates the 10 necessity of a separate operation to form a clearance for the hook of the extractor. Furthermore, the forming of this cut or clearance 57 in the barrel and the consequent permitting of the rotation of the extractor without impairing the 15 efficiency of the rifle permits a further simplification of the construction of the action and particularly the construction of the breech bolt in that the breech bolt in this rifle is made in one solid piece instead of having to make the breech 20 member in two parts with a forward end only reciprocating and with its rear end or attached part rotating in order to lock the breech bolt by the turning of the handle.

The cut or opening 58 in the breech bolt in effect eliminates the part of the wall 64 on the 25 bolt head which is opposite the loading and extracting aperture 34 when the breech bolt is in forward and locked position so that it is possible to see whether or not a cartridge is in the rifle without opening the action. The forwardly 30 tapering formation of the cut or clearance 57 in the barrel, however, makes a possible observation of the rim or flange of the cartridge in the rifle much more easy and certain and available 35 at various angles of the rifle. If the rear face of the barrel were carried straight out to the periphery of the barrel instead of being removed by the cut 57, the rear end of the cartridge would be at the bottom of a very narrow deep groove 40 and would be in most conditions too shaded or darkened by the overhanging metal to enable the shooter to tell with certainty whether or not the rifle is loaded. It will thus be seen that the vent opening provided by the combined cut 45 or clearance 57 in the barrel and the cut or opening 58 in the breech bolt forms a convenient and trustworthy visual indication of whether there is a cartridge in the rifle.

The breech bolt 29 is circular in cross section 50 and cylindrical in outline. The forward end in the main is solid but its rear half is tubular in form providing a chamber 68 open at its rear end and bounded at its forward end by a transverse wall 69 where the solid forward half of the 55 breech bolt begins. In this chamber 68 is slid-
60 ingly mounted the striker 31. In this rifle the striker is cocked by hand, that is the striker is drawn back manually by the shooter grasping the rear portion of the striker that projects beyond the rear end of the breech bolt as seen at the left of Figs. 1, 10 and 11 and as seen at the right hand end of Fig. 13. This rear end or tail of the striker also projects beyond the rear end of the receiver when the breech bolt is in closed 65 position but not cocked as appears in Fig. 1. After the striker has been moved back to cocked position shown in Fig. 14, it is automatically retained and held in that position by the finger 39 on the sear 32 at once springing up into an opening 70 in the bottom wall of the hollow striker where the rear side of the finger of the sear engages the shoulder 71 at the back of said opening 70 in the striker. The arrangement of the parts at this cocked position is well shown in 75 Fig. 14 and also in Fig. 6 where the rear end of

the receiver and also the rear lower end of the chambered part of the breech bolt and also a small part of the chambered portion of the striker are cut away on purpose to show the finger of the sear extending through the guiding cut 5 38 in the rear end of the receiver and through the clearance cut 12 in the rear lower portion of the wall of the breech bolt adjacent its rear end and into the opening 70 in the bottom wall 10 of the striker.

The drawing back of the striker by the shooter pulling upon the tail of the striker compresses the coiled spring 75 mounted within the central bore 76 of the striker and encircling a considerable part of the shank of the striker retaining 15 bolt 77. The head 78 of this bolt is to the rear of the action while its forward end extends into a centrally-located longitudinally extending hole 54 provided in the forward solid half of the breech bolt. Slightly back from its forward end 20 this striker-retaining bolt 78 is screw-threaded to fit the screw-threaded portion of the said hole 54.

The inner end of the breech bolt handle 36 is provided with a tenon 36^a which projects transversely of the breech bolt into a correspondingly shaped and close-fitting mortise 29^a in the breech bolt some distance forward of the wall 69 in the said breech bolt. The tenon 36^a extends well past the center of the breech bolt and is 30 provided with a hole 36^b through which the striker-retaining bolt 77 extends on its way into the portion of the solid breech bolt forward of said mortise. It will now be seen that the striker-retaining bolt 77 thus forms without the 35 use of any extra parts a very effective means for absolutely locking the handle 36 to the breech bolt.

After the parts of the breech bolt are assembled it is very necessary that the ultimate adjustment by screwing the striker-retaining bolt 77 forward be maintained, and that the unscrewing of said striker-retaining bolt 77 from the breech bolt be prevented by positive means that will withstand the jar and vibration of the 40 repeated firing of the rifle and of the back and forth movement given to the breech bolt as the rifle is used. I have provided such a positive locking means without the use of any extra parts by using the short transversely extending arm 50 78 of the extractor 65. This extractor 65 is L-shaped in side elevation as appears from Fig. 21 and also from Fig. 10 and preferably its short arm is circular in cross section as also is the hole 79 extending transversely through the 55 breech bolt slightly forward of the handle 39. After the exact position of the striker-retaining bolt 77 is once determined its forward end is cut or punched off as by a round punch held transversely against the end of the said bolt 77 that 60 extends into the hole 54 in the breech bolt. The shearing off of this forward part of the bolt 77 by a round punch forms a concave surface at the front end of said striker-retaining bolt against which fits the round short arm 78 65 of the extractor. It will then be seen that when the extractor 65 is placed in position with its short arm 78 projecting into hole 79 of the breech bolt and with the body of the extractor placed in the longitudinally extending recess 80 70 provided in the upper side of the breech bolt as the parts are seen in Fig. 10, the said short arm 78 by fitting into the concave surface of the front end of the striker-retaining bolt 77 will hold that bolt 77 positively from unscrewing no 75

matter what the jar or vibration may be. In theory and even in practice the nice determination of the correct position of the striker-retaining bolt 77 may be determined by actually screwing it up to the proper extent in the breech bolt so that a small part of its forward end projects into the hole 79 in the breech bolt. With the breech bolt 29 and the striker-retaining bolt 77 held in this relative position, a round punch of the proper diameter may be passed down through the hole 79 and then driven past the striker-retaining bolt 77 thus operating to shear its forward end off at the precise point required and leaving the front end of said bolt concave to permanently fit the round short arm 78 of the extractor.

It will be understood that the extractor 65 is made of proper resilient material as spring steel so that after its short arm is mounted in the hole 79 in the breech bolt the necessary resiliency for the hook at the forward end of the extractor to spring up over the flange of the cartridge and then settle down at the front of the flange of the cartridge as the breech bolt is moved into forward position is provided by the resiliency of the extractor. It will be understood of course that the short arm 78 of the extractor fits very snugly into its hole 79 so that the pressure of the rim or flange of the cartridge against the sloping forward face of the hook of the extractor does not operate to pry the extractor bodily from the breech bolt nor the short arm of the extractor from its hole. As a further safe-guard, however, and in order to hold the said extractor permanently in the breech bolt the metal of the breech bolt at the sides of the extractor recess, especially towards the rear end of the recess, is burred over or staked over into the recess above the adjoining part of the extractor as indicated at the points 81. The form and proportion of the blade type firing pin 82 is clearly shown in Figs. 19 and 20 of the drawings which are respectively side and edge views thereof. The said firing pin is conveniently formed of a strip of flat metal of the proper thickness, length and structure. It is slidingly mounted in the forward solid portion of the breech bolt which is provided with a deep slot 83 of a width equalling the thickness of the firing pin and of a depth somewhat greater than the width of the firing pin. It is retained in the breech bolt and especially from sidewise displacement therefrom when the breech bolt is removed from the rifle by staking over the higher edge of the slot 83 above the adjoining edge of the firing pin more or less as indicated by overlapping ears 83a. (See Fig. 24.)

The approximate angular disposition of the firing pin slot 83 relative to the breech bolt is best shown in Fig. 24. In other words, the slot 83 does not extend radially of the breech bolt but it extends in from one side of the breech bolt a little bit more than half way through the breech bolt so as to carry the firing point 84 at the front end of the firing pin into line with the rim of the cartridge so that when the trigger is pulled the striker moves forward and gives to the firing pin the necessary firing blow to fire the cartridge. For this purpose the slot 82 slants past the center of the breech bolt as it extends in and locates the firing pin at the inner end of said slot opposite the rim of the cartridge instead of opposite the center of the cartridge. On the other forward corner of the firing pin is another projection 85 spaced laterally from the firing

point 84 and extending forward slightly farther, say about one-hundredth of an inch more or less than does the real firing point 84. This projection 85 as will be plainly seen in Fig. 24 is spaced out from the rim of the cartridge and comes opposite the rear face of the barrel 60 at zone A spaced appreciably out from the edge of the chamber. (Fig. 23.) The function of this projection 85 is to strike the said zone A on the rear face of the barrel 60 before the firing point 84 can strike the anvil on the rear face of the barrel immediately at the edge of the chamber in case the rifle is snapped when there is no cartridge in the barrel. The anvil is the space immediately at the edge of the chamber and on the rear face of the barrel included by the larger zone B shown on Fig. 23 in dotted lines and indicating the area of the firing point 84. These very simple and relatively cheap rifles are especially intended for and largely used by boys and youths and are very often snapped when there is no cartridge in the rifle. The repeated snapping of a rifle under such circumstances tends to allow the firing point of the firing pin to burr over or batter down the regular firing anvil part of the rear face of the barrel because the anvil is at the unsupported edge of the chamber. Such battering or indentation of the anvil upon the barrel soon spoils the effective regular action of the rifle in that the rifle having such a battered anvil does not support the forward edge of the flange of the cartridge rigidly enough and accurately enough for the firing pin to give the cartridge the proper firing blow and consequently such a rifle may occasionally or often mis-fire although a good cartridge is in place. By using a blade-type firing pin and providing the extra projection 85 spaced from and separate from the regular firing point 84, but striking the barrel at a point or zone A apart from the firing anvil of the barrel and which extra projection is so constructed and shaped as to strike the barrel if there is no cartridge in place before the firing pin can strike the anvil, the useless battering of the anvil is avoided. The construction and co-operation of the parts in this gun are such that when there is no cartridge in the gun and the gun is snapped, the striker comes to the end of its forward motion slightly before the firing pin's extra point 85 reaches the barrel and the firing pin after the striker stops, continues and completes its forward motion only under its own momentum. This momentum of the firing pin is not sufficient to distort its extra point 85 (the firing pin being of harder metal than the barrel) nor to batter down the engaged portion zone A of the rear face of the barrel in view of that zone A being well away from the edge of the chamber and so strongly supported in contrast to the anvil which is at the edge of the chamber.

Where the whole front end of the firing pin is tangential to the rim of the cartridge as in this gun (as distinguished from a radial relation) it is a decided advantage to have the points 84 and 85 separated by a recess as the presence of the recess reduces the area of the rim of the cartridge that has to be pushed in when the firing blow is given.

On the inner side of the firing pin 82 there is provided a recess 86 of such depth that into it extends the short arm 78 of the extractor. This recess is of such length that it allows the proper longitudinal back and forth movement of the firing pin 82 but the opposite ends of the said recess by engaging the said short arm of the ex-

tractor prevent the said firing pin from sliding lengthwise farther than required in its regular action and especially operates to hold the firing pin properly assembled in the breech bolt at 5 all times and especially when the breech bolt is removed from the rifle.

In this rifle I have provided a mechanism wherein the striker 31 is of the rebounding type and wherein one spring namely coiled spring 75 10 performs the functions both of a main spring and a rebound spring. Details of this mechanism, especially the relative position of the different parts of the mechanism, are best shown in the enlarged sectional views, Figs. 13, 14 and 15. 15 As already mentioned the rearward half of the breech bolt 29 is provided with a chamber 68 open at its rear end and closed at its forward end by the wall 69. The striker-retaining bolt 77 has the rearward portion of its shank extending 20 longitudinally through the longitudinal axis of the chamber 68 and its forward end passes into a centrally located hole 54 extending some distance forward of the wall 69 in the solid part of the breech bolt and is fixed in position therein 25 by the screw-threaded engagement of the forward end of said striker-retaining bolt with the rearward screw-threaded end of said hole in the breech bolt as already outlined. The body of the striker 31 is generally cylindrical in form as 30 appears from the different detailed outside views thereof, Figs. 16 to 18, and at the rear is provided with the tail portion 73 which consists of the reduced diameter portion 74 and to the rear thereof the enlarged ring-like portion or cocking 35 knob 87 preferably knurled at its periphery. The reduced size of the part 74 together with the enlarged ring-like and knurled portion 87 afford a good gripping surface to be grasped by the shooter's thumb and finger when the striker is to be 40 pulled back against the tension of the spring 75 for cocking the rifle. The main bore 76 of the striker is circular in cross section and extends for its full diameter for almost the full length of the striker. At its forward end, however. 45 there is a reduced diameter passage 88 providing in the material of the striker at the rear end of said passage 88 a strong annular shoulder 89 against which fits the forwardly facing annular shoulder 90 at the forward face of the enlarged 50 annular flange 91 of the forward collar 92 which has a central aperture therein by means of which the collar is slidingly mounted upon the striker-retaining bolt 77. The enlarged rearward flange portion 91 of this collar slidingly 55 fits the main bore 76 of the striker and the reduced diameter of the main and forward portion of said collar fits slidingly in the small forward passage 88 of the striker. The striker or main spring 75 is mounted within the main bore 76 60 of the striker and is coiled about the striker-retaining bolt 77 and its forward end bears against the rear face 93 of the forward collar 92. The rear end of the said spring 75 bears against or 65 is engaged by the forward face 94 of the rearward collar 95 which is slidingly mounted within the striker bore 76 and upon the shank of the retaining bolt 77. This rearward collar 95 is in turn held in place within the bore of the striker 70 by the rearward end of the striker having a constricted opening conveniently formed by the metal at the rear end of the striker being suitably pressed inwardly forming an annular ring 96 of sufficient extent to confine the rearward 75 collar 95 to the bore of the striker. The opening

in this ridge 96, however, is of sufficient diameter to let the head 78 of the striker-retaining bolt 77 pass therethrough into the main bore of the striker where at certain positions of the mechanism the forward face of said head 78 engages the rearward face of the rearward collar 95 and thereby operates to let said rearward collar 95 be a support fixed against any further rearward movement by said end of the spring 75 when the striker is moved bodily rearwardly as 10 during the cocking operation of the rifle. 15

Fig. 13 shows the striker and other co-operating parts in the location they occupy when the striker is at neutral or re-bounded position; that is, after the rifle has been fired or snapped and the striker has gone back to re-bounded position and the rifle reloaded, closed and locked. In this position the tail or thumb-piece of the striker and a small part of the body of the striker immediately ahead of the tail projects rearwardly from the chamber 68 of the breech bolt. The forward end of the forward collar 92 is at its most forward position; that is, with its front end engaging the front wall 69 of the bore of the breech bolt. The rearward collar 95 is at its most rearward position relative to the striker and its rear face engages the forward side of the ridge 96 at the back of the striker and also engages the forward face of the head 78 of the striker-retaining bolt 77. The coiled spring 75 extends for its maximum working length between the rear face of the enlarged flange 91 of the forward collar 92 and the forward face 94 of the rearward collar 95 and the spring at this position is under partial minimum working compression. At this position the upstanding finger 39 on the sear 32 has sprung upwardly ready to engage at its rearward side the forwardly facing shoulder 97 formed by a recess or safety or rebound notch 98 in the lower portion of the wall of the striker some distance forwardly of the tail of 30 the striker. This recess 98 extends to a uniform depth around an appreciable part, say about one-third of the circumference of the striker as seen in different positions in Figs. 16, 17 and 18. Forward of this uniform depth portion the wall of 35 said recess slants outwardly again forming a slanting or cam surface 99 which operates to cammingly force the finger 39 out of the safety recess 98 when the striker is pulled rearwardly as 40 during the cocking operation thereof. It will be 45 noted that in this neutral or re-bounded position the striker 31 is spaced slightly back from its extreme fired or forward position and so leaves a space at the forward end of the chamber 68 in front of the front face of the striker. In this re-bounded position of the striker this slightly retracted position of the striker allows the firing pin 82 to be retracted from engaging the cartridge and the rear end of the firing pin projects into 50 the chamber 68 and so is ready to be engaged by the striker as appears in dotted lines in Figs. 13 and 14. 55

By reason of the striker being held back by the sear engaging the safety notch 98, the gun can- 60 not be accidentally fired by a blow upon the tail of the striker. 65

To move the striker from this neutral or re-bounded position shown in Fig. 13 to the cocked position of the rifle shown in Fig. 14 the tail of 70 the striker is grasped by the shooter and drawn rearwardly to the position of the parts shown in Fig. 14. During this movement the head 78 of the striker-retaining bolt of course remains fixed as its position is permanent relative to the breech 75

bolt and so the rearward collar 95 remains fixed and forms a support for the rear end of the spring 75. This spring has been compressed during this rearward motion of the striker due to the forward end of the spring being engaged by the forward collar 92 which has moved rearwardly with the rearward motion of the striker due to the engagement of the forwardly facing shoulder 90 of the forward collar 92 being engaged by the rearward shoulder 89 upon the forward part of the striker. During this retraction of the striker 31 the upwardly extending sear finger 39 has engaged the slanting cam face 99 upon the striker and said sear finger 39 has been depressed against the tension of the sear so as to ride along the cam face 99 and then along the lower or outer side of the striker forward of said cam face until as the striker is brought to cocked or retracted position the tension of the sear is able to again advance inwardly this finger 39 into the full cock hole or opening 70 in the bottom wall of the striker with the rear face of said finger engaging the forwardly facing shoulder 71 at the rear of said opening 70. The finger of the sear now holds the striker 25 in rearward and cocked position against the tension of the now more greatly compressed spring 75. It will be seen that in this position the head 78 of the striker-retaining bolt is some distance within the rearward end of the bore of the striker. It will be noted also that the forward collar 92 is in the same position relative to the striker that it was in the re-bounded position as shown in Fig. 11; that is, the forward end of the reduced diameter part of said collar projects forwardly of the front face of the striker. The front face of the striker likewise is moved proportionately farther back from the wall 69 of the breech bolt and especially from the still projecting rear end of the firing pin 82 which is to be struck sharply by the striker when released by the sear by the pulling of the trigger. As soon as the sear finger 39 has moved into the full cocked hole or opening 70 of the striker that finger holds the striker in cocked position and the shooter's hand may be released from the tail or thumb piece of the striker.

In this cocked position of the rifle as shown in Fig. 14 the spring 75 is compressed to its maximum working compression and minimum working length and is through the forward collar 92 exerting a force urging the striker 31 forward, but movement of the striker is arrested as long as the sear finger 39 is in engagement with the shoulder 71 of the full cocked recess or hole 70.

Upon the trigger being pulled the sear 32 is drawn away from the striker and particularly the sear finger 39 is disengaged from the full cock recess or opening 70 of the striker and the compressed spring 75 then causes the striker to fly forward. As it flies forward it gains momentum and carries the striker to the neutral or re-bounded position shown in Fig. 13 under the direct force of the spring at which rebounded position the forward collar 92 has its forward end engage the rearwardly facing wall 69 and so stop the collar 92. The momentum, however, already given to the striker causes the striker to move still further forward and the striker carries with it the firing pin 82 to make its firing blow upon the cartridge and finally makes the forward end of the striker seat against the said wall 69 at the front end of the chamber of the breech bolt. The position of the parts at this instant, namely the firing position, but prior to the rebound is shown in Fig. 15. It will be understood that this forward flying of the striker is done so rapidly that

it comes to this position before the shooter can really release his hold upon the trigger and so the sear finger 39 is still shown away from the striker. It will be seen that the actual firing stroke given to the firing pin is accomplished by the last part of the forward movement of the striker which is a movement entirely of momentum. During this last part of the forward movement of the striker, that is, its movement after the front end of the forward collar 92 is stopped by the wall 69, the spring 75 is being compressed again to slightly more than its minimum working compression and to slightly less than its maximum working length because its forward end is held by the rear end of the collar 92 while its rearward end is being pushed in by the last part of the forward travel of the striker which carries the rear collar 95 forward from the head of the retaining bolt 71. The amount that the coil spring is further compressed after the striker passes neutral position shown in Fig. 13 is shown by the shorter space that the spring occupies between the said two collars as may be seen by comparing Fig. 13 with Fig. 15. This difference may also be seen by comparing the immediate engagement of the rear collar 95 with the retaining bolt head 78 as seen in Fig. 13 with the forwardly spaced position of the rear collar 95 relative to said bolt head 78 as seen in Fig. 15. This change in position of parts as mentioned now enables the said spring 75 to function as a rebound spring in that the compression of the spring at once operates to move the striker back from the fired position shown in Fig. 15 to the neutral position shown in Fig. 13. The compression given to the spring 35 operates to exert a rearward force upon the rearward collar 95 and therefore to the rear end of the striker and this force manifests itself in moving the striker rearwardly so that its forward end is no longer in contact with the wall 69 but is spaced back therefrom and also spaced back from the rear end of the firing pin. After the striker thus comes back to this rebounded position as shown in Fig. 13, the shooter releases the trigger and the sear finger 39 springs upward into the safety notch 98 and the rear end of said finger is again ready to engage the shoulder 71 and hold the striker from accidental forward movement.

Rotation of the striker in the breech bolt is prevented by means of a key 100 pressed inward from the wall of the breech bolt and slidily engaging a keyway 101 extending longitudinally of the top of the body of the striker as appears in Figs. 10 and 16.

The wall of the hollow rear half of the breech bolt is cut away for its whole length making a slideway 102 located in the portion of the breech bolt that is at the bottom when the breech bolt has been unlocked by swinging its handle upwardly and is being moved back or forth by said handle being moved back and forth through the passage 35 therefor in the receiver. As best appears in Fig. 10 this slideway 102 is in line with the firing pin slot 83 and reaches to the rear end thereof. The rear end of this slideway 102 it 50 will be seen communicates with the clearance cut 72 in the rear end of the breech bolt through which the sear finger 39 projects upwardly to engage the striker by entering the safety notch or recess 98 in the striker when the striker is in re-bounded position. Accordingly the partial rotation of the bolt in the unlocking thereof swings the breech bolt so that the sear finger 39 passes into the rear end of the long slideway 102 and during retraction of the breech bolt said finger 75

slides through this slideway 102 with said finger 39 first engaging the cam surface 99 of the striker and then the bottom surface of the body of the striker and then moving inwardly and upwardly along the second cam face 103 until finally the finger 39 strikes sharply the rear end of the firing pin 82. This drives the firing pin forwardly in the breech bolt and its firing point 84 is snapped forward against the opposite rim portion of the cartridge and thus the firing pin functions also as the ejector in striking the rear of the cartridge diametrically across from the extractor hook and thus operating to throw the cartridge from the gun.

15 The passageway 102 is continued a short distance forwardly of the wall 69 so that the sear finger is able to push the firing pin slightly farther forward than said pin is moved by the firing pin during the firing operation. After the firing pin 20 has been moved forward to cause the firing pin to function as an ejector the said firing pin comes to the end of its forward travel as limited by the short arm of the extractor engaging the recess in the firing pin as already described, and 25 thereafter the engagement of the sear finger with the rear end of the firing pin retains the bolt in the gun so that the sear thus acts as the bolt stop preventing the bolt being withdrawn from the receiver beyond its normal retracted position. 30 If the breech bolt is to be entirely withdrawn from the receiver the sear finger is removed from this stopping position by pulling on the trigger which depresses the sear in substantially the same way as occurs during the firing operation. 35 On account of the peculiar angular shape of the trigger 33 and its articulation with the sear 32 and the contact of these parts normally with the receiver 27 as shown in Fig. 2 and again in full line position in Fig. 6, it will be obvious that 40 a firing operation cannot be made by forward motion of the finger piece of the trigger for the reason that the trigger is positively locked against having its finger piece moved forward from normal position. The elements insuring such locking are the contact of the rear side of the trigger projection 41 with the rearward face of the slot 40 in the receiver, the contact of the upper face of the straight horizontal part 42 of the trigger as at zone 107 with the lower side of the receiver 45 immediately thereabove and the contact of the forward face of the upper part of the central vertical portion 43 of the trigger with the forward face of the aperture 44 in the sear as at zone 108, it being understood that the sear is not movable lengthwise of the gun. After this trigger 50 has been pulled it will come to a position as shown in dotted lines in Fig. 6 where the trigger is locked against any further clockwise movement. This is accomplished partly by the engagement of the trigger projection 41 against the top and forward face of the slot 40 and partly by the engagement of the trigger at its interior angle with the upper and lower edges of the sear at the rear face of the sear aperture 44. 55 In the modification of the connection of the trigger to the receiver shown in Figs. 27 and 28, the sear 32 and trigger 33 are of substantially the same construction as already described and in general co-operate with each other and with the 60 receiver as heretofore described. The projection 41^a at the upper end of the trigger, however, fits into the widened front part 105 of a notch 106 extending in from the rear end of the receiver 29 at its bottom. This arrangement causes the 65 sides of the widened front of the notch to hold

the trigger from sidewise movement and yet allows the rear face of the widened part of the notch by engaging the rear side of the trigger projection 41^a to lock the trigger finger piece from being moved forward from normal position 5 in combination of course with the other inter-engaging points still present as above outlined with regard to the main form of trigger connection. After the trigger has made its firing motion, the trigger of this modification is locked 10 from further similar clockwise movement by the engagement of the front face of the trigger projection 41^a with the front face of the widened recess 105 in combination of course with the other contacting parts still present in this modified 15 form of trigger connection.

The rifle can be fired only by being properly closed, locked, cocked and having the trigger pulled. The rifle cannot be cocked until the breech bolt is fully closed and locked because the 20 full-cock notch cannot be brought into register with the sear finger unless the breech-bolt is in that position.

An accidental discharge due to the cocking knob of the striker slipping from the grasp of the 25 fingers in drawing the striker back to the full-cocked position is impossible due to the fact that in travelling forward the striker would have its half-cock notch engaged by the sear finger.

Accidental discharge from rapid and violent 30 closing of the bolt accompanied by forward movement of the striker through its re-bound phase due to its velocity and inertia is impossible on account of the fact that the sear finger will engage the half-cock notch before the striker can 35 move into its rebound phase.

What I claim as new and desire to secure by Letters Patent is:

1. In a single shot bolt action firearm of the rim-fire type the combination of a barrel having 40 a cartridge-receiving chamber at its rear end, a hollow receiver located to the rear of the barrel and having a loading and ejecting opening therethrough and a breech bolt reciprocatingly mounted in said receiver and having at its forward end 45 a head space recess adapted, when the breech bolt is closed, to support the rear end of a rim-fire cartridge in firing position, a firing pin movably mounted in the breech bolt to be projected forwardly into the said head space at the rim supporting zone thereof, the said breech bolt having at its front end and freely open through said flange directly outwardly to the atmosphere a gas venting and observation cut extending from said recess to the periphery of the breech bolt through 50 substantially the portion thereof that is adjacent the said loading and ejecting aperture of the receiver when the bolt is closed and locked.

2. In a bolt action firearm of the rim-fire type the combination of a barrel having a cartridge- 60 receiving chamber at its rear end, a hollow receiver located to the rear of the barrel and having a laterally arranged loading and ejecting opening therethrough and a breech bolt reciprocatingly mounted in said receiver and having at 65 its forward end a head space recess partially bounded by a forwardly extending flange and adapted, when the breech bolt is closed, to support the rear end of a rim-fire cartridge in firing position, a firing pin movably mounted in the 70 breech bolt to be projected forwardly into the said head space at the rim supporting zone thereof, the said breech bolt having at its front end and freely open through said flange directly outwardly to the atmosphere a gas venting and ob- 75

servation cut extending laterally from said recess to the periphery of the breech bolt through substantially the portion thereof that is adjacent the said loading and ejecting aperture of the receiver when the bolt is closed and locked.

3. In a bolt action of the rim-fire type firearm the combination of a barrel having a cartridge-receiving chamber at its rear end, a hollow receiver located to the rear of the barrel and having a loading and ejecting opening therethrough and a breech bolt reciprocatingly mounted in said receiver and having at its forward end a head space recess adapted, when the breech bolt is closed, to support the rear end of a rim-fire cartridge in firing position, a firing pin movably mounted in the breech bolt to be projected forwardly into the said head space at the rim supporting zone thereof, the said breech bolt having at its front end and freely open through said flange directly outwardly to the atmosphere a gas venting and observation cut extending from said recess to the periphery of the breech bolt through substantially the portion thereof that is adjacent the said loading and ejecting aperture of the receiver when the bolt is closed and locked, said barrel also having on the loading side only a gas-venting and observation cut adjoining the front of the said cut in the breech bolt, and reaching from the rear face of the barrel close to the bore 30 out to the periphery of the barrel and substantially co-extensive with the said cut in the breech bolt.

4. In a bolt action firearm of the rim-fire type the combination of a barrel having a cartridge-receiving chamber at its rear end, a hollow receiver located to the rear of the barrel and having a loading and ejecting opening therethrough and a breech bolt reciprocatingly mounted in said receiver and having at its forward end a head space recess adapted, when the breech bolt is closed, to support the rear end of a rim-fire cartridge in firing position, a firing pin movably mounted in the breech bolt to be projected forwardly into the said head space at the rim supporting zone thereof, the said breech bolt having at its front end and freely open through said flange directly outwardly to the atmosphere a gas venting and observation cut extending from said recess to the periphery of the breech bolt through substantially the portion thereof that is adjacent the said loading and ejecting aperture of the receiver when the bolt is closed and locked, said barrel also having on the loading side only a gas-venting and observation cut adjoining the front of the said cut in the breech bolt, and reaching from the rear face of the barrel close to the bore out to the periphery of the barrel and substantially co-extensive with the said cut in the breech bolt and having its forward wall sloping outwardly as it extends forwardly.

5. In a bolt action firearm of the rim-fire type the combination of a barrel having a cartridge-receiving chamber at its rear end, a hollow receiver located to the rear of the barrel and having a laterally arranged loading and ejecting opening therethrough and a breech bolt reciprocatingly mounted in said receiver and adapted to make a partial rotation therein and having at its forward end a head space recess adapted, when the breech bolt is closed, to support the rear end of a rim-fire cartridge in firing position, a firing pin movably mounted in the breech bolt to be projected forwardly into the said head space at the rim supporting zone thereof, the said breech bolt having at its front end and freely open through said

flange directly outwardly to the atmosphere a gas-
venting and observation cut extending from said
recess to the periphery of the breech bolt through
substantially the portion thereof that is adjacent
the said loading and ejecting aperture of the re-
ceiver when the bolt is closed and locked, said
barrel also having on the loading side only a gas-
venting and observation cut axially adjacent to
and circularly registering with the front of the
said cut in the breech bolt, and reaching from
the rear face of the barrel close to the bore out
to the periphery of the barrel.

6. In a bolt action firearm of the rim-fire type the combination of a barrel having a cartridge-receiving chamber at its rear end, a hollow receiver located to the rear of the barrel and having a laterally arranged loading and ejecting opening therethrough, a breech bolt reciprocatingly mounted in said receiver and adapted to make a partial rotation therein and having at its forward end a head space recess partially bounded by a forwardly extending flange and adapted, when the breech bolt is closed to support the rear end of a rim-fire cartridge in firing position, a firing pin movably mounted in the breech bolt to be projected forwardly into the said head space at the rim supporting zone thereof, the said breech bolt having at its front end and freely open through said flange directly outwardly to the atmosphere a gas venting and observation cut extending from said recess to the periphery of the breech bolt through substantially the portion thereof that is adjacent the said loading and ejecting aperture of the receiver when the bolt is closed and locked and a hooked extractor carried by and projecting forwardly of the breech bolt into a clearance cut provided in the rear end of the barrel on the loading side only and extending circumferentially for the extent of the partial rotation of the extractor, said barrel also having said extractor clearance cut in the rear end of the barrel extended circumferentially beyond the travel of the extractor and out to the periphery of the barrel, the entire cut in the barrel forming a gas-venting and observation cut axially adjacent to and circularly registering with the front of the said cut in the breech bolt. 15 20 25 30 35 40 45

7. In a bolt action firearm of the rim-fire type the combination of a barrel having a cartridge-receiving chamber at its rear end, a hollow receiver located to the rear of the barrel and having a laterally arranged loading and ejecting opening therethrough, a breech bolt reciprocatingly mounted in said receiver and adapted to make a partial rotation therein and having at its forward end a head space recess partially bounded by a forwardly extending flange and adapted, when the breech bolt is closed to support the rear end of a rim-fire cartridge in firing position, a firing pin movably mounted in the breech bolt to be projected forwardly into the said head space at the rim supporting zone thereof, the said breech bolt having at its front end and freely open through said flange directly outwardly to the atmosphere a gas venting and observation cut extending from said recess to the periphery of the breech bolt through substantially the portion thereof that is adjacent the said loading and ejecting aperture of the receiver when the bolt is closed and locked and a hooked extractor carried by and projecting forwardly of the breech bolt into a clearance cut provided in the rear end of the barrel on the loading side only and extending circumferentially for the extent of the 70

partial rotation of the extractor, said barrel also having said extractor clearance cut in the rear end of the barrel extended circumferentially beyond the travel of the extractor and out to the periphery of the barrel and sloped outwardly and forwardly beyond the front end of the extractor,

the entire cut in the barrel forming a gas-venting and observation cut axially adjacent to and circularly registering with the front of the said cut in the breech bolt.

NICHOLAS L. BREWER. 5
